The ornamental design for a storage device for optical media such as CDs, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a storage device for optical media such as CDs embodying our new design;

FIG. 2 is a left side view thereof;

FIG. 3 is a right side view thereof;

FIG. 4 is a front elevational view thereof;

FIG. 5 is a rear elevational view thereof;

FIG. 6 is a top plan view thereof; and,

FIG. 7 is a bottom plan view thereof.

The outermost broken lines showing the logo, hinges and latch throughout the views, represent the unclaimed boundaries of the design. The boundary lines themselves, forming no part of the claim. The features within the broken lines illustrate the portions of the design that form no part of the claim.
